UNITED STATES PATENT OFFICE.

HENRY CÔTÉ, OF WEST WARREN, MASSACHUSETTS, ASSIGNOR TO WARE MACHINE & LOOM COMPANY, OF WARE, MASSACHUSETTS, A CORPORATION OF MASSACHUSETTS.

LOOM.

1,035,114.

Specification of Letters Patent.

Patented Aug. 6, 1912.

Application filed August 27, 1910. Serial No. 579,255.

To all whom it may concern:

Be it known that I, HENRY CÔTÉ, a citizen of the United States, residing at West Warren, county of Worcester, and State of Massachusetts, have invented an Improvement in Looms, of which the following description, in connection with the accompanying drawing, is a specification, like characters on the drawing representing like parts.

This invention relates to looms and particularly to the binder and associated devices for holding the shuttle in the box and preventing rebound thereof.

Looms are commonly provided with a binder, and a binder spring which acts continually on the binder, said binder operating to frictionally engage the shuttle as it enters the box and hold it in proper position therein. Where the binder is acting at all times on the shuttle the picker must act with sufficient force not only to throw the shuttle across the lay, but also to overcome the friction of the binder against the shuttle as it is leaving the shuttle box and the added force which must be given to the blow of the picker to overcome the frictional resistance of the binder against the shuttle involves the use of considerable power, especially where a large number of looms are being run in a single mill.

It is the object of my invention to provide a novel binder which will act to apply frictional resistance to the shuttle as it enters the box whereby said shuttle will be brought to rest without any rebound, but which will relieve the shuttle from all frictional pressure while it is being picked. In Patent No. 962,495, June 28, 1910, is shown a device of this general nature in which a cam on the crank shaft is employed for relieving the shuttle from the pressure of the binder at the time that the shuttle is to be picked. In the device herein shown, I have done away with binder springs and employ a simple device which will secure the desired object of applying the binder pressure to the shuttle when it enters the box and relieving said shuttle from said pressure when it leaves the box.

In the drawings I have shown two embodiments of my invention, one involving the use of a front binder, and the other involving the use of a rear binder.

Figure 1 is a fragmentary view of a loom

with the lay and shuttle box in section showing my invention applied to a loom having a binder on the rear of the shuttle box; Fig. 2 is a similar view showing one way of applying my invention to a loom having a binder on the front of the shuttle box; Fig. 3 is a modification of the device shown in Fig. 1.

In the drawings 3 designates part of a loom frame, 4 the lay, 5 the shuttle box, 6 the shuttle therein, 7 the binder, 8 the lay swords, and 9 the connecting rod leading to the crank. These parts are or may be of any suitable construction and form no part of the present invention.

The binder 7 which is usually pivoted at one end and is adapted to swing inwardly, is acted on by a finger 10, the movement of which is controlled by a cam 11 carried by the frame of the loom, the construction being such that as the lay beats up, the finger 10 is swung forwardly to cause the binder 7 to engage the shuttle, while when the lay is on its back center the arm 10 is allowed to swing away from the binder to relieve the pressure thereon. There are various ways in which this motion may be given to the finger 10 from the cam 11, and in the embodiment shown in Fig. 1 said finger 10 is mounted on an arm 12 which is pivoted to the lay or the lay-sword at 13, so that it may swing upwardly and downwardly. The finger 10 is shown as having a roll 14 which is adapted to engage the upper edge of the cam 11. The cam 11 has the low portion 15 and the high portion 16, and is so shaped that when the lay is on the back center the roll will engage the low portion of the cam, while when the lay is on the front center, the roll 14 will engage the high portion of the cam. This cam 11 may be of any suitable construction and may be secured in place in any appropriate way. I have herein shown it as provided at one end with a stem 17 which is bolted or otherwise secured to the frame of the loom, as at 18, and if desired the free end of the cam may be supported in a bracket or holder 19. The particular manner of securing the cam to the loom frame, however, is not important.

I prefer to shape and place the cam so that the roll 14 will pass from the high to the low portion of the cam just before the shuttle is picked, which is usually when the

crank is about on the bottom center. I may provide a similar device for each shuttle box, or the two arms 12 at each end of the shuttle box may be mounted on a rod which 5 extends the length of the lay such, for instance, as the ordinary protector rod so that a cam 11 at one end of the loom will suffice. In either event, however, when the lay is in its backward position with the roll 14 on 10 the low portion of the cam, there will be no pressure applied to the binder and the shuttle can be freely picked without having to use any more force than is necessary to throw it across the lay. As the lay moves 15 forward and the roll 14 engages the high portion 16 of the cam, the arm 12 will be swung upwardly, thus causing the finger 10 to act on the binder and apply frictional pressure to the shuttle. The change from 20 the high to the low portion of the cam may be so timed that when the shuttle is picked it will be relieved from the binder pressure, but when it enters the box at the other end it will be subjected to the binder pressure, 25 and this pressure will be maintained until the lay moves backwardly again.

I have shown the finger 10 as adjustably mounted on the arm 12, and as being held in 30 adjusted position by a clamping screw 20. In Fig. 2 I have shown an arrangement adapted for use with a front binder and in this figure the finger 10 which acts on the binder 7 is pivoted to the lay at 21 and is provided with a rearwardly-extending arm 35 110 constituting a cam member. The upper edge of said cam is shaped to present the low portion 150 and the high portion 160. Secured to the loom frame is a bracket 22 which carries a roll 23 adapted to engage the 40 upper edge of the cam arm 110. The arrangement of these parts is such that when the lay is in its backward position, as seen in Fig. 2, the low portion 150 of the cam engages the roll 23 so that the binder pressure 45 is relieved, while as the lay beats forward and the high portion 160 of the cam engages the roll 23, the arm 10 will be turned to cause the binder pressure to be applied to the shuttle. This cam member is so shaped 50 that the roll 23 will pass from the high to the low portion and vice versa just as the shuttle is picked so that the shuttle will be

relieved from binder pressure at the time it is picked, but when it enters the box will be subjected to said pressure.

55

Instead of having the cam member 11 rigid as in Fig. 1, I may yieldingly attach it to the loom frame, as shown in Fig. 3, in which case it is hinged to the loom frame at 24 and is supported at its outer end by a 60 spring 25 sustained in a bracket 26. A stop 27 may be employed to limit the swinging movement of the cam. If the parts are properly adjusted, the device will work satisfactorily with the cam 11 rigidly sustained, 65 but under some circumstances it may be desirable to adopt a construction in which the cam is yieldingly sustained, and in Fig. 3 I have shown one way in which this might be accomplished.

70

My invention is not limited to the construction illustrated, as various changes in the parts might be made without departing from the invention.

Having fully described my invention, 75 what I claim as new and desire to secure by Letters Patent is:—

In a loom, the combination with a lay having a shuttle box thereon and a binder, of an arm pivotally sustained by the lay and extending backwardly therefrom, a finger adjustably mounted on said arm and adapted to engage the binder, and a bar extending in the direction of movement of the lay and situated so that said finger continuously engages the upper edge thereof during both the forward and backward movements of the lay, said upper edge of the bar having a high portion at one end thereof and a low portion at the other end thereof, the high 85 portion being situated to be engaged by the finger during the latter part of the forward movement of the lay and during the first part of the backward movement thereof whereby the binder is pressed against the 90 shuttle all the time it is in the box.
